(57) **CLAIM**

The ornamental design for a shakable container with agitator, as shown and described.

DESCRIPTION

FIG. 1 is a top perspective view of a shakable container with agitator showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom perspective view thereof;

FIG. 9 is a top perspective view thereof with the lid in open position;

FIG. 10 is a front view thereof with the lid in open position;

FIG. 11 is a rear view thereof with the lid in open position;

FIG. 12 is a left side view thereof with the lid in open position;

FIG. 13 is a right side view thereof with the lid in open position;

FIG. 14 is a top plan view thereof with the lid in open position; and,

FIG. 15 is a bottom plan view thereof with the lid in open position.
